S. H. Dudley.

Scrapper.

No 11,021.

Patented July 6, 1854.

UNITED STATES PATENT OFFICE.

SAMUEL H. DUDLEY, OF MILTON, CONNECTICUT.

ROAD-SCRAPER.

Specification of Letters Patent No. 11,021, dated June 6, 1854.

To all whom it may concern:

Be it known that I, SAMUEL H. DUDLEY, of Milton, in the county of Litchfield and State of Connecticut, have invented a new and useful Improvement in Road-Scrapers; and I hereby declare the following to be a full and true description thereof, reference being had to the drawings herewith presented, which drawings constitute a part of 10 said description.

My improvement consists in constructing the scraper in such manner and form as to enable the operator to continue the work taking the earth from the sides of the road 15 and delivering it in the middle without the trouble and delay of upsetting or of lifting the scraper in order to discharge the load. By this means I am enabled to proceed along the side of the road raising the earth 20 along the edge of the scraper and delivering it constantly at the end in the middle of the road. I also construct the connecting hooks and chains in such manner as to allow the scraper to be turned over if required without falling on the chains.

See the drawing Figure 1 is an oblique view of the scraper in operation (A,) is the main plank or board of the scraper (C,) is the chain so arranged as to draw the 30 board diagonally forward and may be adjusted to any desired angle. (H,) is the handle. (B,) is the bow or hook by which the chain is attached to the back of the

board. It may be seen at Fig. 2 which shows the elevation; the height of the bow 35 allows the scraper to be thrown over without interfering with the chains; but having them attached on the back side is more important on account of delivering the earth at the end, as it leaves the front side clear 40 of any obstruction.

In using the common scraper in the old way half of the time and labor are spent in backing or turning about in order to load and unload all of which is obviated by my 45 manner of constructing and using; for by drawing the scraper obliquely the earth is constantly raised from the side and delivered at the end of the scraper in the middle of the road.

I do not claim the invention of scrapers, chains, hooks, or either of them as such, but

What I do claim as my invention and desire to secure by Letters Patent is— 55

The combination of the bow or bows (B,) with the scraper for the purpose set forth, and in a manner substantially as herein described.

In testimony whereof I hereto subscribe 60 my name in presence of two witnesses.

SAMUEL H. DUDLEY.
